UNITED STATES PATENT OFFICE

147,870

DESIGN FOR AN ASH TRAY

William L. Russo, Long Beach, N. Y.

Application April 27, 1946, Serial No. 129,016

Term of patent 7 years

(Cl. D85—2)

To all whom it may concern:

Be it known that I, William L. Russo, a citizen of the United States, residing in Long Beach, Nassau County, State of New York, have invented a new, original, and ornamental Design for an Ash Tray, of which the following is a specification, reference being had to the accompanying drawing, forming a part hereof, in which the figure is a perspective view of an ash tray embodying my new design.

I claim:

The ornamental design for an ash tray, as shown.

WILLIAM L. RUSSO.
